[57] CLAIM

The ornamental design for a pencil case, as shown and described.

DESCRIPTION

FIG. 1 is a front perspective view of a pencil case showing my new design;

FIG. 2 is a rear perspective view;

FIG. 3 is a front elevational view in an opened condition;

FIG. 4 is a rear elevational view with the flaps in an extended condition;

FIG. 5 is a front elevational view of FIG. 4;

FIG. 6 is a front elevational view of FIG. 4 in an opened condition;

FIG. 7 is a bottom plan view of FIG. 5; and,

FIG. 8 is a top plan view of FIG. 5.

The ring binder notebook depicted by means of broken lines in FIGS. 1 and 2 has been shown for illustrative purposes only and forms no part of the claimed design.

FIG. 1

FIG. 2
